LAYOUT INSTRUMENT

Ellis Thompson, West Palm Beach, Fla.

Application January 17, 1952, Serial No. 266,869

3 Claims. (Cl. 33—88)

1

This invention relates to new and useful improvements in layout instruments and the primary object of the present invention is to provide a device for measuring roof pitch, elbow mitre, various angles, drill sizes and sheet thicknesses, and which may also be employed for leveling purposes.

Another important object of the present invention is to provide an all-purpose carpenter instrument, whereby the various measurements required in construction work may be readily and quickly determined.

A further object of the invention is to provide an instrument of the aforementioned character that is extremely simple and practical in construction and which includes a base section and a pair of arms pivotally secured to the ends of the base section together with means carried by one of the arms for engaging and locking the arms together and alongside of said base section.

A still further aim of the present invention is to provide a layout instrument that is simple and practical in construction, strong and reliable in use, efficient and durable in operation, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side view of the present invention assembled for use;

Figure 2 is a view similar to Figure 1, but showing the arms folded in side by side relation to each other and the base section;

Figure 3 is a plan view of Figure 2;

Figure 4 is an enlarged detail sectional view taken substantially on the plane of section line 4—4 of Figure 1; and,

Figure 5 is a fragmentary perspective view of one end of one of the arms illustrating the clip means forming part thereof.

Referring now to the drawings in detail, wherein for the purpose of illustration, there is disclosed a preferred embodiment of the present invention, the numeral 10 represents a rigid base section whose ends are secured to swingable, rigid arms 12 and 14 by pivots 16 and 18. Arms 12 and 14 are so positioned or mounted on their pivots that the same lie in planes spaced parallel to each other to permit swinging movement of the arms to a position where the same are dis-

2

posed in side by side relationship with respect to each other as well as the base section.

5 A resilient or flexible U-shaped guide clip 20 is integrally formed with the outer free end of the arm 12. One leg portion 22 of the clip 20 is integrally formed with the arm 12 and is flush therewith. The other leg portion 24 is formed with a notch 26 so shaped as to provide a pair of aligned index lugs 28. One end of a fastener 30 is fixed to the leg portion 22 and extends through an aperture 32 in the leg portion 24. A wing nut 34 is threaded on fastener 30 to permit adjustment of the leg portion 24 toward or away from leg portion 22.

10 The arm 14 is curved and its pivoted end is formed with a notch 36 adapted to receive the fastener 30 when the arms are folded in side by side relation, whereupon tightening of the nut 34 will secure the arms 12 and 14 together and alongside of the base section 10.

15 Base section 10 is provided with a series of longitudinally spaced apertures 38 of various sizes of diameter with indicia 40 adjacent each aperture to indicate the diameter of the apertures. These apertures will permit the sizes of drills to be determined. The lower edge of the base section 10 is also formed with a plurality of longitudinally spaced notches 42 of various widths and indicia 44 on the base section disposed adjacent the notches indicate the width of the notches, whereby the thickness or gauge of sheet material, such as metal, may be readily determined.

20 Arm 12 supports a level unit 46 at its central portion. The arm 12 is provided with graduations 48, preferably in inches with fractions of the inches distinguished by small perforations 50 that may accommodate a pencil point or scribe.

25 Arm 14 is provided with longitudinally spaced graduations 52 in degrees with spaced perforations 54 for fractions of degrees that will accommodate a scribe. Additional graduations 56 on the arm 14 are provided for determining roof pitch in conjunction with the arm 12 and base section 10. Fractions of the graduations 56 are designated by perforations 58 in the arm 14.

30 A highly important feature is accomplished through the provision of indicia and graduations 60 along the convex edge of arm 14, since this set of graduations will permit determination of the mitre line of pipe elbows without complicated mathematical computations. The mitre line on any round elbow from a two-piece elbow to and including a nine-piece elbow may readily 35 be determined in a convenient manner by using

the pointer in conjunction with the base section 10 and graduations 60.

The pitch of a roof may be quickly and readily determined and pattern layouts made by an indication of such roof pitch by the registering of pointer 28 with graduations 58 along the concave edge of arm 14, thereby obviating the necessity of employing triangulation work and for mathematical tables.

In practical use of the present invention, the 10 arm 12 being slidably connected to the arm 14 will form a desired angle with the base section which angle will be designated between the lugs 28. A roof pitch may be determined or laid out in the same manner.

Many other uses of the device are readily suggested by the structure shown, and thus, the instrument is capable of being used for various types of carpenter or construction work.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having thus described the invention, what is claimed as new is:

1. A layout instrument comprising a base section, a pair of arms pivotally secured to the ends of said base section, one of said arms having graduations thereon, a slide and index member carried by the other arm and slidably received on the said one arm, and means carried by the slide and index member for lockably engaging the said other arm to lock the arms together, said slide and index member including a substantially U-shaped resilient clip, said locking means comprising a fastener joining the limbs of said clip.

2. The combination of claim 1 wherein said one of said arms is provided with a notch adjacent its pivot receiving the fastener when the arms are folded one beside the other and alongside of said base section.

3. The combination of claim 1 wherein the graduations on said one of said arms includes a scale for indicating the mitre line of round elbows from a two piece elbow to and including a nine piece elbow.

ELLIS THOMPSON.
